UNITED STATES PATENT OFFICE.

FRANK CORDES, OF PITTSBURGH, PENNSYLVANIA.

BOTTOM-POUR LADLE.

1,338,001.

Specification of Letters Patent. Patented Apr. 27, 1920.

Application filed August 22, 1918. Serial No. 250,926.

To all whom it may concern:

Be it known that I, FRANK CORDES, a citizen of the United States, residing at Pittsburgh, in the county of Allegheny and State of Pennsylvania, have invented a new and useful Improvement in Bottom-Pour Ladles, of which the following is a full, clear, and exact description, reference being had to the accompanying drawings, forming part 10 of this specification, in which:

Figure 1 is a sectional view through a portion of a bottom pour ladle and a stopper, showing one form of my invention.

Fig. 2 is a plan view of the nozzle, and 15 Fig. 3 is a sectional perspective view on the line III—III of Fig. 2.

This invention relates to an improvement in bottom pour ladles, and is designed to provide a cheap and efficient device 20 whereby the quantity of metal passing through the pouring spout may be varied and also to provide a spout for pouring a plurality of small streams without affecting the volume of the flow, so that the gases 25 can more readily escape from the metal during the pouring.

The precise nature of my invention will be best understood by reference to the accompanying drawings, which will now be 30 described, it being premised, however, that various changes can be made in the details of construction and the general arrangement of the parts, without departing from the spirit and scope of my invention as defined in the appended claims.

Referring to the drawings, the reference character 2 designates the body of the ladle which is provided with a refractory lining 3. 4 is the pouring spout or nozzle mounted 40 in the bottom of the ladle and which is provided with a cylindrical recess 5 in the upper portion thereof. Communicating with this recess and extending through the other end of the pouring spout 4 are a plurality of openings 6. These openings are 45 outwardly flaring and are arranged to divide the metal flowing from the ladle into a plurality of streams of small diameter. 7 designates the stopper which is of the usual 50 form for entering or closing the recess 5 to stop the flow of metal through the nozzle.

As is well known to those familiar with the art of pouring castings, and particularly ingots, better castings can be made if 55 the stream of metal flowing to the mold is of small diameter, as the gases within the metal can more readily escape from a small

stream than from a large stream. Heretofore attempts have been made to pour the castings by reducing the size of the opening 60 in the nozzle in order to permit the escape of the gases, but this reduction in the size of the pouring opening has also reduced the speed of the flow of metal. By my improved device, I am enabled to reduce the 65 size of the streams without affecting the speed of the flow of the metal. My nozzle is also very well adapted for pouring castings of different sizes, as all of the openings may be left open when pouring castings 70 requiring a large volume of metal and one or more of the openings can be plugged up with clay when pouring smaller castings.

The advantages of my invention result 75 from the provision of a ladle having a plurality of pouring openings therethrough which are arranged to be closed with a single stopper.

I claim:

1. A bottom pour ladle having a removable refractory pouring spout therein, said spout having an annular flange adapted to be supported on a seat in the bottom of the ladle, said spout having a cylindrical opening in its upper part adapted to be closed 85 by means of a stopper, and a plurality of openings communicating with said recess and extending through the spout to feed a common mold, substantially as described.

2. A bottom pour ladle having a removable refractory pouring spout in the bottom thereof, said pouring spout having an annular flange seated on a support in the bottom of the ladle, their being a cylindrical tapered opening in the upper portion of the 95 spout communicating with the interior of the ladle, a stopper for closing said opening, their being a plurality of outwardly flaring openings communicating with said opening and extending through the spout, substantially as described.

3. A bottom pour ladle comprising a removable refractory pouring spout, said spout having a recess in its upper part adapted to be closed by means of a stopper, 105 and having a plurality of openings communicating with said recess and extending entirely through said spout co-axially with said recess and adapted to form a plurality of small feeding openings for a common 110 mold, substantially as described.

In testimony whereof I have hereunto set my hand.

FRANK CORDES,
